CLAIM

The ornamental design for a jar body, as shown and described.

DESCRIPTION

FIG. 1 is a right side elevational view of the jar body of our new design, the left side elevational view being a mirror image thereof;

FIG. 2 is a front elevational view thereof;

FIG. 3 is a rear elevational view thereof;

FIG. 4 is a top plan view thereof; and,

FIG. 5 is a bottom plan view thereof.

The broken line showing of the finish portion of the jar in FIGS. 1-4 is for illustrative purposes only and forms no part of the claimed design.
